BOOK AND LEAF HOLDING DEVICE FOR
PRINTING MACHINESCharles G. Krakenberg, New York, N. Y., assignor
to Checkmaster Systems, Inc., New York, N. Y.,
a corporation of New York

Application August 5, 1950, Serial No. 177,797

8 Claims. (Cl. 101—407)

1

My present invention relates generally to printing, and has particular reference to a machine for successively imprinting the leaves of a bound book.

More particularly, the invention relates to an improved table or printing bed whereby the book to be imprinted may be more efficiently located and held in a predetermined imprinting position, and the leaves held down as they are successively imprinted, lifted, and turned about the bound edge of the book.

While certain phases of the invention are not restricted to the printing or holding of any particular type of book, the invention is primarily intended for use in relatively small printing mechanism such as those which are suitable for manual operation by relatively unskilled operators. An example of such printing machine is that which is used by banks to imprint a depositor's name and address, or other personal information, on the individual leaves of a "personalized" small-size check book.

A machine of the specialized character referred to comprises essentially a bed or table upon which the check book is held, and an overhead platen which contains the printing form (name of depositor, etc.) and which is brought down by manipulation of a hand lever or otherwise to make an imprinted impression on successive checks. After being imprinted, each check, which is in reality a leaf of the book, is turned by hand to expose the next underlying check. The turned leaves are ordinarily held in their turned positions by one hand of the operator.

The invention relates specifically to a device for holding the turned leaves or imprinted checks in their turned positions, thereby greatly facilitating the operation of the machine. By the use of the present holding device the imprinting machine may be operated at a considerably accelerated rate. The operator can devote his full attention to the manipulation of the printing mechanism and the coordinated turning of the individual checks, and need not be distracted by any effort to hold the checks in their turned positions. The holding device of this invention makes it impossible for an imprinted and turned check or checks to spring back, an occurrence which would delay operation or result in spoiled checks.

In addition to the foregoing object of the invention, a further object is to provide a holding device for the turned leaves which is part of a larger device having provisions for positioning the check book in proper location on the printing bed or table. Another object is to provide

2 a device as described which will accommodate not only those check books which are stapled or otherwise secured together at a narrow or transverse edge of the checks but also check books which are stapled or otherwise secured together along a longitudinal edge of the checks.

I achieve the foregoing and such other objects of invention as may appear or be pointed out herein, by means of the preferred embodiment of my invention illustrated in the accompanying drawings, wherein:

Figure 1 is a top view of the improved device as applied to books secured together at a narrow (transverse) edge;

Figure 2 is an elevational cross-section taken on the line 2—2 of Fig. 1;

Figure 3 is an end view taken in the direction of line 3—3 of Fig. 1;

Figure 4 is an elevational cross-section taken transversely across the device, on the line 4—4 of Fig. 1;

Figure 5 is a transverse cross-section similar to Fig. 4 and showing a book in place;

Figure 6 is a top view of the device as applied to books secured together along a long edge;

Figure 7 is an elevational cross-section taken on the line 7—7 of Fig. 6; and

Figure 8 is an elevational cross-section taken transversely across the device, on line 8—8 of Fig. 6.

I have chosen to illustrate the printing bed or table of a machine especially adapted for imprinting check books. The machine shown is set up in Figs. 1—5 for imprinting books in which the checks are stapled or otherwise secured at a narrow edge (the right in Figs. 1—2) of the checks. The bedplate of the machine is designated 9; the check book 8 is placed in a predetermined position on plate 9 so that the printing type (not shown) will imprint in the proper space provided on the individual checks. For this purpose a main abutment bar 10 is secured to table 9, as by screws 11, Fig. 1; and at the right of main abutment bar 10, an end abutment plate 12 is also secured to table 9. End abutment plate 12, as best seen in Fig. 1, has a pair of short legs 13, 14 so that legs 13, 14 together with web 12 of the plate form a shallow recess; the inside distance between legs 13, 14 is only a little larger than the width of check book 8, so that the right end thereof (which is the end at which the checks are stapled together) is held snugly by end abutment plate 12, with the long side (upper, in Fig. 1) of the book contacting main abutment bar 10.

End abutment plate 12 is secured to the plate

or bed 9 by an end bar 15, which overlies it, see Fig. 2, and which is secured to bed 9 by screws 16, 16, Fig. 1, passing through end abutment plate 12, Fig. 2.

Immediately to the left (Fig. 1) of end bar 15 are a pair of transverse bars 17, 18, of which 17 is the upper, and 18 the lower bar. Transverse bars 17, 18 extend beyond legs 13, 14 of the end abutment plate 12, and their ends are secured together by bolts 19, (Figs. 4, 5) which pass through holes or passages 7 in the bed plate 9, so that the upper transverse bar 17 and the lower transverse bar 18, held rigidly together by bolts 19, 19, may move up and down as a unit, relative to plate 9. A compression coil spring 6, encircles each of bolts 19 between the underside of plate 9 and lower bar 18, so that the unit 17-18-19 is normally urged downwardly, with upper transverse bar 17 close to plate 9, as in Fig. 4. When a check book is positioned on the machine, its right end (Figs. 1-2) is slipped under upper bar 17, the compression of springs 6 holding the book firmly in place.

The individual checks, such as the uppermost one in Fig. 1 designated 5, are lifted and turned to the right after being imprinted. The device for holding the checks or leaves in their turned positions comprises a pair of members designated generally 20, 20. Members 20, 20 are preferably fabricated of strip metal which is twisted 90° upon itself to form a lower shank 21 and an upper portion presenting an inside strip 22 and an outer finger 23; see Fig. 3. The distal end of finger 22 is bent slightly to form a short lip 24. Members 20, 20 are located at opposite ends of transverse bar 15, see Figs. 1 and 3, being pivotally secured to the outer side of bar 15 by means of a screw 25, the stem of which passes through a hole in shank 21. A tensile spring 26, the ends of which are anchored at the shanks 21 of members 20, normally urges members 20, toward each other. Referring to Fig. 3, the ends of bar 15 at which the members 20 are pivotally mounted, are slightly recessed to provide a shoulder 15* at each end against which the inside edge of the shanks 21 of members 20 abut to limit their turning toward each other under urgency of spring 26.

Each of the members 20 has the shape of a question mark, and in the normal position of members 20 the lips 24 of their fingers 23, are separated from one another by a distance somewhat less than the width of a check, which is indicated in Fig. 3 by the single check 3 and the plurality of checks 21. The single check 3 shown in Fig. 3 represents a check being turned after having received an imprint. In order that check 3 may pass lips 24 of the finger members (to reach and be added to, the plurality of held checks or leaves 20), members 20 turn outwardly through a slight angle (as shown in dot-and-dash positions). It should be pointed out that the check itself is flexed slightly in the process of adding it to the checks already held by members 20; hence, the extent of outward turning of members 20 is very slight. In any event, it should be noted that lips 24 in their normal positions are closer together than the width of the check so that they overlie the accumulation of turned checks 21 and hold them in turned positions.

The machine can be adjusted for check books in which the checks are stapled or otherwise secured along a long edge, as shown in Figs. 6-8. In this case the check book 8, Fig. 6, is placed with its free edge 7, i. e., the long edge opposite the stapling, in contact with main abutment bar

10. The end abutment plate (12-13-14) of Figs. 1-5 is not used in this case; instead, a plate 30, Fig. 6, is secured to table 9, as by corner screws 31. Referring to Fig. 7 it will be seen that a narrow and thin strip or shim 32, 32 is placed under plate 30 at each side, so as to provide a central clearance under plate 30 wherein the back cover 1 of the check book is passed.

A second longitudinal bar 33, Fig. 6, is then secured to table 9, as by end screws 34, 34. (Referring to Fig. 1, table 9 is provided with a pair of spaced tapped holes 34* to receive screws 34, 34; and the plate 30 may if desired remain in place, as shown in Fig. 1, as it does not interfere with the use of the device with check books or pads stapled or otherwise secured at a narrow or transverse end, as in Fig. 1). At the ends of bar 33, which engages the long bound edge of the book, are pivotally mounted a pair of members 20, impelled toward one another by tensile spring 26, as already described. The turned leaves, such as 2* in Fig. 8, are held by members 20, 20 in the same manner as more fully described with reference to Figs. 1-5.

The device, when used for check books secured along a longitudinal edge, may be provided with a pair of spring clips 40 which engage and frictionally hold the free edge portions of the checks of book 8, as shown in Fig. 6. Spring clips 40 are held at spaced points along bar 10, Fig. 6, and may be hooked about bar 10, as shown in Fig. 8, bar 10 having a recess 10* at its lower side, in which leg 41 of the spring clip may be inserted and held.

The operation will be apparent. For example, where the machine is hand operated, the operator moves the printing head up and down with one hand, and successively lifts and turns the leaves of the book with the other. As each leaf is turned it readily passes through the space between the opposed leaf engaging members 20, and as the latter resume their normal relationship they bear down on the turned leaves beneath them and hold them against any return movement. By correlated movements of the operator's hands the printing of a number of successive leaves can be accomplished in an unusually simple and expeditious manner. When all the leaves have been imprinted, they are readily released by spreading the members 20 apart, and the book can then be released from the table.

Where the book is bound along its long edge, each successive leaf, after imprinting, is first pulled edgewise from beneath the clips 40 before it is lifted and turned.

It will be understood that many of the details herein described are merely illustrative, and that those skilled in the art may readily make changes in some of these details without necessarily departing from the spirit and scope of the invention as expressed in the appended claims.

Having thus described, and illustrated my invention, what I desire to secure by grant of Letters Patent is:

1. In a machine for imprinting individual leaves of a book in which the leaves are secured along a narrow side thereof, a table for supporting said book thereon, a main abutment bar on said table, an end abutment plate on said table and having a pair of short end legs presenting a recess, the inside edge of one of said legs being aligned with the inside edge of said main abutment bar whereby said book may be held in imprinting position with its bound end in said recess, and means adjacent to said end abutment plate for holding leaves which have been turned

about said narrow side of the book away from the imprinting position of the unturned leaves, said means comprising a pair of opposed members having ends extending inwardly over the table toward each other, and means mounting said members on said table for movement toward and away from each other.

2. The combination with the elements set forth in claim 1 of a bar arranged close to, and substantially parallel to, said end abutment plate, and adapted to overlie said book, and spring means for pressing said bar against the book.

3. In a machine for imprinting individual leaves of a book in which the leaves are secured along a long side thereof, a table for supporting said book thereon, an abutment bar on said table, a plate supported on said table in a slightly spaced relation thereto, said book being positioned with its leaves in overlying relation to said plate and with its back cover received beneath said plate, the edge of the book opposite said bound side engaging said abutment bar, a second bar engaging said bound side of the book, and means adjacent to said second bar for holding leaves which have been turned about said long side of the book away from the imprinting position of the unturned leaves, said means comprising a pair of opposed members having ends extending inwardly over the table toward each other, and means mounting said members on said table for movement toward and away from each other.

4. The combination with the elements set forth in claim 3 of a pair of spring clips at spaced points on said first abutment bar and adapted to engage and yieldably hold down the free ends of said unturned leaves.

5. In a machine for successively imprinting the individual leaves of a bound book, a table, means for locating said book on said table with the bound edge in a predetermined position, and a yieldable holder arranged adjacent to said bound edge and adapted to engage and hold down successive leaves as they are lifted and turned about said bound edge, said holder comprising a pair of opposed members having ends extending inwardly over the table toward each other, means mounting said members on said table for movement toward and away from each other, and a spring normally urging at least one of said members toward the other.

6. In a machine for successively imprinting the individual leaves of a bound book, a table, means for locating said book on said table with the bound edge in a predetermined position, and a

yieldable holder arranged adjacent to said bound edge and adapted to engage and hold down successive leaves as they are lifted and turned about said bound edge, said holder comprising a pair of opposed members each of which has the shape of a question mark with upper free ends of yieldable material and extending inwardly toward each other relative to the table, said members serving as yieldable fingers between which the leaves are releasably held down.

7. In a machine for successively imprinting the individual leaves of a bound book, a table, means for locating said book on said table with the bound edge in a predetermined position, and a yieldable holder arranged adjacent to said bound edge and adapted to engage and hold down successive leaves as they are lifted and turned about said bound edge, said holder comprising a pair of opposed members each of which has the shape of a question mark with upper free ends of yieldable material and extending inwardly toward each other relative to the table, said members serving as yieldable fingers between which the leaves are releasably held down, said members being mounted on said table for movement toward and away from each other, and a spring normally urging at least one of said members toward the other.

8. In a machine for imprinting individual leaves of a book, said leaves having a predetermined dimension and secured in said book at an edge parallel to said predetermined dimension, a pair of members each having a leaf engaging portion, said members being arranged at the ends of the bound edge of the book and pivotally mounted to present their leaf engaging portions in facing relation, and spring means urging said members toward each other, means on the table for limiting the inward movement of the members toward each other to less than said predetermined dimension of the leaves whereby leaves turned about said bound edge of the book are retained by said members which move away from each other as each successive leaf is turned and pushed past said members to join the previously turned and retained leaves.

CHARLES G. KRAKENBERG.
